UNITED STATES PATENT OFFICE.

RALPH D. MERSHON, OF NEW YORK, N. Y.

ELECTRODE FOR ELECTROLYTIC APPARATUS.

1,326,134.

Specification of Letters Patent. Patented Dec. 23, 1919.

Application filed April 2, 1917. Serial No. 159,146.

To all whom it may concern:

Be it known that I, RALPH D. MERSHON, a citizen of the United States, residing at New York, county and State of New York, have

5 invented certain new and useful Improvements in Electrodes for Electrolytic Apparatus, of which the following is a full, clear, and exact description.

This invention relates to electrodes for 10 use in condensers, storage batteries, and other electrolytic apparatus, and its chief object is to provide an electrode of aluminum or other suitable metal, having for exposure to the electrolyte a superficial area 15 which is large in proportion to the bulk of the electrode. Another object is to provide an electrode that not only has the large superficial area indicated, but which also possesses the mechanical strength needed to 20 meet the various conditions of actual use. To these and other ends the invention consists in the novel features hereinafter described.

One form of the invention is illustrated 25 in the accompanying drawing, in which—

Figure 1 is an elevation of the electrode. Fig. 2 is a vertical section on line 2—2 of Fig. 1.

30 Fig. 3 is a horizontal section on line 3—3 of Fig. 1.

Fig. 4 is a detail perspective view.

My improved electrode consists essentially 35 of a crimped plate 10 of sheet metal, preferably very thin sheet metal, say a few thousandths of an inch thick, surrounded and carried by a suitable supporting frame.

As stated, the plate 10 is crimped, that 40 is, it is corrugated in form, the folds, crimps, or corrugations being deep and close together but out of contact with each other throughout their length, and their sides are substantially parallel to each other. Preferably the folds are of considerably greater depth than width, as clearly shown in 45 Fig. 3. To facilitate circulation of the electrolyte and flow of current through the same when the electrodes are in use the crimps, or folds are perforated at their bends, as at 11. Preferably the perforations 50 are mere slits, with their edges spread apart as indicated in Fig. 4, to enlarge the openings. In this way apertures of good size are obtained without diminishing the area of the metal exposed to the electrolyte 55 as would be the case if parts of the metal were actually punched out.

The crimped plate may be made all in one piece, but it is more convenient to make it in two or more sections, for instance three, as shown in Fig. 1. 60

The supporting frame is preferably all metal, and in the form shown it consists of vertical angle bars forming side members 12, and upper and lower cross members 13, riveted or otherwise fastened together. To 65 increase the stiffness of the cross members they are slotted at the ends, as at 14, and the intermediate portions are bent to give them a curved cross section, as shown in Fig. 2. The edges of these bent portions 70 may project beyond the surface of the plate 10 so that when the electrode is laid down on a table or other flat surface the crimped plate will not come in contact therewith. The flanges on the side bars 12, extending 75 oppositely to the bent portions of the cross members, perform a like function for the other side of the plate.

For the purpose of holding the plate 10 securely in the frame the inner edges of 80 the upper and lower members 13 are seated in slots 15, Fig. 2, in the upper and lower edges of the plate.

Electrical connection of the crimped plate 85 with the external circuit is preferably made through the supporting frame. For this purpose at least one member of the frame is made of metal, preferably the upper cross member, and the terminals of the crimped plate are welded or soldered thereto. These 90 terminals can be conveniently formed by cutting strips 16 from the edges of the final folds at the sides of the plate sections. The terminal strips thus provided are bent up and inserted in slits 17 cut in the upper 95 cross member of the supporting frame and are soldered or welded thereto. By preference the slits are formed in tongues 18 cut out of the bent portions of said cross members so that the strips will be gripped by the 100 spring pressure of the two halves of the tongues as well as by the soldered or welded connection therewith.

The flat end portions or ears 19 or the 105 upper and lower cross members afford convenient points for grasp by supporting means (not shown) to hold the electrode upright in the electrolytic cell, and one or both of the ears on the upper member can be used as a point of connection with the external 110 circuit in any suitable manner, not shown.

A corrugated sheet of the thickness men-

tioned, say a few thousandths of an inch, composed of aluminum or similar metal, is so easily deformed that it has heretofore been difficult if not impossible to use metal of 5 such thinness, inasmuch as when arranged side by side in the electrolyte the plates are apt to bulge at the center or bend at the edges and thus come into contact one with another. But by mounting each plate in a 10 separate frame, as described above, the individual plates are made practically rigid and the proper spacing and separation in the electrolyte is easily maintained. Moreover, when the corrugations in the plate are 15 deep, as in the electrode shown, bending or flexure of the plate is liable to bring the edges of some of the corrugations too close to, or into contact with, each other, thereby interfering with the free circulation of the 20 electrolyte; whereas it is desirable to have as free circulation as possible so as to minimize local heating and insure more even distribution of the heat generated in the apparatus, and also to facilitate the freeing of 25 bubbles from the surface of the plates.

It is to be understood that the invention is not limited to the specific construction herein described, but can be embodied in other forms without departure from its 30 spirit.

I claim:—

1. An electrode for electrolytic apparatus, comprising a crimped plate of sheet metal having apertures extending across the 35 crimps or folds, and a supporting frame surrounding the plate, having cross members extending through said apertures to support the plate in said frame.

2. An electrode for electrolytic apparatus, comprising a crimped or folded plate of sheet metal having slots extending across the 40 crimps or folds, and a supporting frame surrounding the plate, having cross members arranged with their edges seated in said 45 slots to support the plate in said frame.

3. An electrode for electrolytic apparatus, comprising a crimped or folded plate of

sheet metal, a supporting frame surrounding and secured to the crimped plate and having a metallic member, and one or more 50 terminal strips extending from the crimped plate and welded to the said metallic member to afford electrical connection therewith.

4. An electrode for electrolytic apparatus, comprising a crimped plate of sheet metal, a supporting frame surrounding and secured to the plate and having a metallic member, and one or more terminal strips 55 integral with the plate and welded to the said 60 metallic member.

5. An electrode for electrolytic apparatus, comprising a crimped or folded plate of sheet metal having apertures in the bends of the crimps or folds. 65

6. An electrode for electrolytic apparatus, comprising a crimped or folded plate of sheet metal having slots in its edges across the crimps or folds, a supporting frame surrounding the plate having vertical and 70 cross-members the latter arranged with their edges seated in said slots to hold the plate in the frame, at least one of the members of the frame being metallic, and a welded connection between the plate and the metallic 75 member.

7. An electrode for the purpose described, comprising a crimped or folded sheet of thin sheet metal having deep folds closely spaced together and of greater depth than width, 80 and a rigid frame surrounding the crimped sheet and serving to maintain the same in proper form.

8. An electrode for the purpose described, comprising a crimped or folded sheet of thin sheet metal having closely spaced folds 85 the sides of which are parallel, and a rigid frame surrounding the crimped sheet and serving to maintain the same in proper form. 90

In testimony whereof I hereunto affix my signature.

RALPH D. MERSHON.
